STRAINER

Filed Sept. 25, 1930

UNITED STATES PATENT OFFICE

LEIGH P. HOFF, OF BALA-CYNWYD, PENNSYLVANIA, ASSIGNOR TO THE ALLEN-SHERMAN-HOFF COMPANY, A CORPORATION OF PENNSYLVANIA

STRAINER

Application filed September 25, 1930. Serial No. 484,307.

This invention relates to strainers, and more particularly to self cleaning strainers adapted to prevent the entry of foreign material into fluid pumps and the like.

5 In a large number of industrial operations it is necessary to pump water or other liquids containing a certain amount of solid abrasive material. Pumps have been designed which are especially suited for pumping liquid containing ash or other abrasive material if the particles of material are not of too great size. It therefore becomes necessary to provide some means of preventing particles of solid material greater than a certain size 10 from entering the pump. A particular instance where my strainer is very advantageous is in a recirculating ash disposal system for a boiler furnace. In this system water under high pressure is discharged 15 through jets or nozzles and the ash from the furnace is carried to a sump by the water so discharged. The sump is provided with a number of baffles which accomplish a partial separation of water and ash and the 20 separated water passes into a baffled off portion of the sump from which it is drawn by a high pressure pump and again discharged 25 through the nozzles.

Although the water and ash may be fairly 30 well separated in the sump, it is important that a strainer be provided in the intake of the high pressure pump to prevent particles of ash from entering the pump and causing excessive wear both on the pump and 35 the nozzles. The strainer also eliminates the danger of clogging the nozzles and the small clearance spaces of the pump.

It is among the objects of my invention, therefore, to provide a strainer particularly 40 adapted for use in the above described apparatus.

A further object of my invention is to provide a strainer adapted to be fitted into the intake pipe of a pump which will prevent 45 large particles of solid material from entering the pump.

Another object is the provision of a self cleaning strainer which is automatic in operation for preventing large particles of solid 50 material from entering a pump.

Another object of my invention is the provision of a strainer which is of simple construction and which may be economically manufactured and is particularly adapted to easy renewal of the wearing parts.

Other objects of my invention will appear from the following description of one form thereof, reference being had to the accompanying drawing in which:

Fig. 1 is a sectional side elevation illustrating my strainer in position in the intake pipe or pump;

Fig. 2 is a plan section taken on the line 2—2 of Fig. 1;

Fig. 3 is a detached perspective view of 65 the screen carrying cage and screen;

Fig. 4 illustrates the position of the screen when water is being pumped;

Fig. 5 illustrates the position the screen assumes when the pump stops, and water 70 flows back through the strainer.

The body of my strainer is made up of an outer cylindrical shell 1 having a flange 2 at its top. A removable cover plate 3 is secured in place on the top of the shell 1 by the bolts 75 4. On one side of the shell 1 is secured a short section of pipe 5 which forms the outlet from the strainer. This pipe 5 is connected to the pump intake pipe 6. A ring 7 is secured in place on the inner surface of the shell 80 1 at a point somewhat below the outlet opening 8. This ring 7 acts as a support for the screen cage 10 and the screen 9.

As is best seen in Fig. 3, the screen is secured at its outer periphery to a ring 11. The 85 upwardly extending members 12 are secured at intervals around the circumference of the ring 11 and are bent inwardly at their upper ends so that they may be welded or otherwise secured together as at 13.

When the pump is in operation, a mixture of water and ash or other solid material will be drawn up to the screen 9 and the water will pass out through the outlet opening 8 to the pump while most of the solid matter will be 95 held back by the screen. When water is flowing through the screen to the pump, the center part of the screen 9 will be bent upwardly, as best seen in Fig. 4, by the action of the water flowing upwardly through it and the 100

pressure of the solid material on its under side. As the outlet opening 8 is above the screen 9, when the pump is stopped the water in the intake pipe 6 and in the upper portion of the strainer housing 1 will flow back down through the screen 9 and flush the solid material collected on the under side of the screen back into the sump. This back flow will also bend the screen downwardly to approximately the position shown in Fig. 5 and this bending action will free any small particles of material which may have become lodged in the mesh of the screen.

The upper end of the screen cage 10 is adapted to abut against the top cover plate 3 and serves to hold the screen 9 down in position against the upward pressure of material on its under side when the pump is operating. This basket also serves as a convenient handle with which to remove the screen when it is desired to change the size of the screen mesh.

It will be noted that the area of the screen 9 in the housing 1 is large compared to that of the outlet pipe 6. Thus the flow through the screen will be relatively slow and wear will be reduced to a minimum. This construction also greatly reduces the power required to draw the liquid through the strainer.

If desired the screen 9 may be made rigid instead of flexible as illustrated and the strainer will still be substantially self cleaning due to the back flow of water therethrough.

From the above description it will be seen that my improved strainer is particularly adapted to be used with pumps which are designed for pumping water carrying solid material. As above explained, my strainer is self cleaning and therefore eliminates the necessity of providing a hand hole for manually cleaning the screen of the strainer at more or less frequent intervals.

Although I have shown and described a preferred form of my invention, it will be seen by those skilled in the art that modifications and variations thereof may be made without departing from the spirit of my invention. I do not therefore, limit myself to the precise details shown and described, but claim as my invention, all embodiments thereof, coming within the scope of the appended claims.

I claim:

1. A strainer comprising an outer shell having a bottom inlet opening and an outlet opening on one side, a removable closure for the top of said shell, a flexible screen disposed within said shell at a point below said outlet opening and means for maintaining the periphery of said screen in fixed relation to the walls of said shell, while permitting movement of the central portion of said screen in a direction parallel to the path of material passing through the strainer.

2. A self cleaning strainer comprising a casing having vertically spaced inlet and discharge openings, said inlet opening being below said discharge opening, a flexible screen extending across said casing between said inlet and discharge openings, and means for maintaining the periphery of said screen stationary relative to said housing while permitting the central portion of said screen to move vertically.

3. In a strainer, the combination of a housing having vertically spaced inlet and outlet openings, said outlet opening being disposed above said inlet opening, and a screen adapted to bend upwardly in its central portion when material is passing through said housing from said inlet to said outlet, and to bend downwardly when material is passing through said housing from said outlet to said inlet.

4. A self cleaning strainer for mixtures of liquid and solid abrasive material comprising, a casing having vertically spaced inlet and discharge openings, said inlet opening being below said discharge opening, a flexible screen extending across said casing between said inlet and discharge openings, and means for maintaining the periphery of said screen stationary relative to said housing while permitting the central portion of said screen to move vertically, said screen being adapted to be flexed upwardly by flow of the mixture from said inlet to said discharge opening and to be flexed downwardly when said flow from said inlet to said discharge opening ceases whereby particles of abrasive material, which have become lodged in the mesh of said screen during said flow from said inlet to said discharge opening, will be dislodged.

In testimony whereof I hereunto affix my signature this 18th day of September, 1930.

LEIGH P. HOFF.
